UNITED STATES PATENT OFFICE.

EADS JOHNSON, OF MORRISTOWN, NEW JERSEY.

DOCKING APPARATUS.

Application filed July 1, 1925. Serial No. 40,716.

My invention relates to an improved apparatus, referred to hereinafter as docking apparatus, and adapted to be used in connection with marine railways, graving docks, and floating docks of both the box and sectional type.

One of the objects of my invention is the provision of an apparatus whereby a ship or other floating property may be hauled out or 10 may be drydocked with a less expenditure of time and labor than is possible with the equipment now employed for such purposes.

A further object of my invention is the provision of an apparatus of the character 15 above referred to, whereby in drydocking a ship, for example, it will be unnecessary to build up the bilge blocks, as the bilge logs forming part of my invention will care for different heights required for the hull of 20 the ship and thereby save both the time and labor formerly required to build up the bilge blocks.

A still further object of my invention is the provision of an apparatus of the character 25 above indicated, wherein it is unnecessary to obtain a plan of the hull of the ship to be docked prior to the docking operation.

A further object is to save the raising of 30 the dock when once lowered to fix bilge blocks for another vessel, as the bilge logs will accommodate any vessel and the dock may remain sunk until raised again after the other vessel has been placed.

In order that my invention may be clearly 35 understood, I will give a brief outline of the plan now followed in drydocking: Under present practice it is customary to obtain, first of all, a docking plan of the ship which 40 is to be drydocked, in order that the bilge blocks may be built up to the desired height and properly located so as to support the ship directly under the bilge. After this work has been done, the dock is sunk and 45 the ship floated in. Before the dock is pumped out, however, care must be exercised in properly positioning the ship so that when the water is finally pumped out the ship will 50 rest in an upright position upon the keel blocks and be supported properly at each side of the keel blocks by the previously built-up bilge block structures. This con-

sumes a great deal of time and requires the services of a skilled operator. After the dock has been sunk again and the ship floated out, it becomes necessary to float the dock again, and after obtaining a docking plan of the next ship to be drydocked to reconstruct the bilge block structure and to sink the dock again before the next ship may be 60 drydocked. In other words, every time a ship is to be drydocked this entire operation must be gone through with.

In my improved apparatus I have provided a construction whereby a great deal of 65 the time consumed in the above described operation can be saved. For example, it is unnecessary with my apparatus to empty the drydock between ships. In other words, the dock is ready to receive a ship as soon as the 70 preceding ship has been floated out.

In the carrying out of my invention I provide a bilge log one end of which is adapted to be pivoted at different heights to or adjacent the keel blocks, this log being brought 75 into contact with the ship's hull and supported in such position by improved bilge blocks which are adapted to be moved lengthwise of the bilge log so as to raise and lower the same to suit hulls of different 80 shapes. This arrangement provides a structure whereby it is unnecessary to know beforehand the plan or shape of the hull to be docked, and after my apparatus is once installed it becomes unnecessary to float the 85 drydock between ships, inasmuch as when one ship is floated out of the dock the dock is all ready to receive the next ship.

In the accompanying drawing an embodiment of my invention has been illustrated 90 more or less diagrammatically but with sufficient clarity to illustrate the invention.

Referring to the drawing in detail, 1 designates diagrammatically a drydock of the floating type, and 2 and 3 the hull of the 95 ship to be docked therein, that portion designated 3 illustrating a portion of the hull either forward or aft of amidships, while 2 designates a portion of the hull amidships. 4 designates bearer logs, upon which the 100 bilge blocks rest and are guided as these blocks are drawn in or out from the center.

Disposed along the longitudinal center line of the dock are keel blocks 5, compris-

ing, as indicated, a built up structure composed of several blocks. There are several of these keel blocks in each installation, as will be understood, the keel of the ship, as 5 the name of these structures implies, resting upon and being supported by these blocks when the drydock has been pumped out or floated.

Each keel block structure carries two bilge 10 logs, designated 7, these logs, as will be apparent from an inspection of the drawings, extending transversely of the dock directly over the bearer logs. These logs are pivoted equidistant each side of the center of the 15 dock or keel blocks. The bilge logs may be of wood or of metal, as desired, and are pivotally attached to the bilge blocks by straps 8 or 10 and pivot 9. By providing more than the one strap the logs may be pivoted 20 at different heights to accommodate different forms of the underbodies of ships.

Supporting the bilge logs, that is to say, the outer or free ends thereof, are bilge blocks which may be in the form of super- 25 imposed blocks 11 spiked or otherwise held to each other. Each of these bilge block structures rests upon one of the bearer logs 4, it being understood that there is a bilge block structure for each bilge log. The lower 30 block of each bilge block is provided with straps 13 engaging beneath a strip 14 formed on or secured to each side of the bearer log, whereby tipping or floating of the bilge 35 block structure relative to the bearer log is prevented.

Carried by each bilge block structure is a half round member 15 having a bearing in a half round metal lined bearing 16 provided in the bilge block. The flat lower side of the 40 bilge log rests upon the flat face of the half round supporting member 15, and inasmuch as the member 15 is rotatable in its bearing and not attached thereto, it will be apparent that this member will always accommodate 45 itself to the bilge log as the bilge blocks are moved along the bearer log. A pair of straps 17 or other means are attached to each bilge block structure and extend upwardly beyond the member 15 and for a short distance overlap 50 the sides of the bilge log, to keep the half round supporting member 15 in position and to assist in proper positioning of the log on the blocks.

As above pointed out, the bilge logs 7 may 55 be of wood or metal, and if constructed of wood, I may weight the outer ends thereof as indicated at 18, to prevent floating out of the straps.

Instead of weighting the bilge logs and in 60 order that the bilge logs 7 may be held against floating upwardly when the drydock is sunk, I provide the cable 18, which is fastened to the bilge block and passes around pulleys 19 and 20 at the ends of the bilge 65 log. This permits of the bilge blocks being

moved along the bearer log while holding the bilge log upon the bilge blocks. The bilge blocks are shifted by any suitable tackle.

From the foregoing it will be seen that in 70 dry docking a ship in a dock equipped with my apparatus, it is merely necessary to float the ship in after the dock has been sunk, without regard to a docking plan of the ship's bottom, and to then float the dock, the 75 bilge logs and bilge blocks being adjusted as the ship finally settles upon the keel blocks. By employing the bilge logs it is apparent that no matter what the shape of the ship's bottom may be, the same will always catch 80 beneath the bilge thereof. It will be seen also that the trouble now experienced in dry-docking, in having the bilge blocks too low so that they do not catch the bilge at all but pass in beyond the same toward the ship's 85 keel, is avoided.

In order that the next ship may be dry-docked, it will be obvious that it is merely necessary to sink the dock, float out the ship previously drydocked, and then float in the 90 next ship. This is possible without knowing beforehand the shape of the hull of the second ship and without floating the dock the second time in order to build up a new bilge block structure, a procedure which is 95 not possible with apparatus at present in use.

I have described my invention specifically in connection with a drydock, but it is to be understood, as stated above, that my apparatus is adapted for use in connection with 100 marine railways and graving docks as well, all of which apparatus are intended to be covered by the expression "docking" or "dry-docking", as the case may be, employed throughout this description.

While I have described a specific embodiment of my invention, it is to be understood that the same may take other forms within the purview of the invention.

What I claim is:

1. In an apparatus of the class described the combination of a bilge log pivoted at one end, a bilge block structure for supporting the free end of said log, and means for adjusting said bilge block structure longitudinally of the log to raise and lower the free end of the log.

2. In an apparatus of the class described the combination of a keel block, straps attached thereto, a bilge log, means for pivoting said log to said straps and constructed to permit of any pivotal point being used, a bearer log, and a bilge block movable along said bearer log and adapted to support said bilge log and to move the same about 115 its pivot.

3. In an apparatus of the class described the combination of a pivoted bilge log, a bilge block for supporting said log, a bearer log, means for preventing side motion of 130

the bilge block relatively to the bearer log, log, means for adjusting said block longitudinally of said logs, and means for preventing lateral displacement of said bilge log relatively to said logs.

and means for preventing lateral displacement of said bilge log relatively to the bilge block.

5. 4. In an apparatus of the class described, the combination of a pivoted bilge log, a June, 1925.

bilge block for supporting said log, a bearer

This specification signed this 30th day of

JUNE, 1925.
